PLASTIC BOTTLE

David G. Hills, Hartford, Conn., assignor to Plax Corporation, West Hartford, Conn., a corporation of Delaware

Application April 10, 1953, Serial No. 24,439

Term of patent 14 years

(Cl. D58—6)

To all whom it may concern:

Be it known that I, David G. Hills, a citizen of the United States, residing at Hartford, State of Connecticut, have invented a new, original, and ornamental Design for a Plastic Bottle, of which the following is a specification, reference being had to the accompanying drawing, forming a part hereof.

Fig. 1 is a perspective view of a plastic bottle embodying my new design;

Fig. 2 is a side elevation thereof; and

Figs. 3 and 4 are top and bottom views of Fig. 2, respectively.

The sides of the bottle not shown are the same as those shown.

I claim:

The ornamental design for a plastic bottle, as shown and described.

DAVID G. HILLS.
